UNITED STATES PATENT OFFICE.

CHESTER I. WAGNER, OF NEW YORK, N. Y., ASSIGNOR TO WAGNER-MOORE, INC., OF NEW YORK, N. Y., A CORPORATION OF NEW YORK.

CODIFIER APPARATUS.

Original application filed January 24, 1917, Serial No. 144,260. Divided and this application filed June 13, 1917. Serial No. 174,415. Renewed January 22, 1924.

To all whom it may concern:

Be it known that I, CHESTER I. WAGNER, a citizen of the United States, and a resident of New York city, New York, have 5 invented certain Improvements in Codifier Apparatus, of which the following description, in connection with the accompanying drawings, is a specification, like reference characters on the drawings designating like parts.

This invention relates to codifier apparatus, the primary object of which is the provision on matter to be filed in filing devices of all kinds, of a numerical designation in such a manner that no separate record, cross index or like record will be necessary to identify the numeric designation with the alphabetic, geographic or subject designation under which the matter is 15 commonly identified, and, in accordance with an important feature of my invention, this numeric designation is arranged to remain on the matter in connection with the ordinary designation, to facilitate the reference to, filing and finding of the matter.

Another important object of my invention is to provide a mechanical means of placing the numeric designation on the matter and by the same operation and at the same time 20 the alphabetic, geographic or subject designation from which the numeric designation is derived, and my preferred means for accomplishing this purpose takes the form of a codifying attachment to a typewriter.

Among other important results accomplished by my invention a notable one is that in large filing systems requiring a number of file clerks, only one (commonly called the chief file clerk) is required to codify the numeric designation from the alphabetic, geographic or subject designation of the matter to be filed or found, the other clerks filing and finding the matter by means of its numeric designation only, thus greatly decreasing the chances of mis-filing, and increasing the speed with which the matter is filed and found.

The various features of my invention will be illustrated and described fully in the accompanying drawings and specification and pointed out in the claims.

In the drawings:

Fig. 1 illustrates a codifier presenting the preferred preassignment, to groups of letters of the alphabet, of digits in the series 1, 2, 3, 4, 5, 6, 7, 8, 9, and 0, with the number digit shown above each group, this codifier serving as a guide in placing the proper number above the name, geographic or subject designation of the matter indexed, when such designation is placed thereon by being written with pen or pencil; the arrangement of the type faces upon the typewriter shuttle shown in Fig. 3 is also in accordance with this codifier when mechanical means, as herein described, are used to print the designation on the matter to be filed.

Fig. 2 illustrates an arrangement of type faces in accordance with my invention by which, when the printing impact is made, each letter has printed above it the number digit from which the numerical identification is codified. The order illustrated is that of the standard typewriter keyboard.

Fig. 3 illustrates codifying devices applied to a typewriter constituting the preferred form of means to effect mechanically by a single operation the imprint upon the matter to be filed of the numerical character constituting the indexing number, and also the alphabetical characters selected previously from the matter to be filed as the significant or designatory portion thereof.

Fig. 4 represents a number of cards with the same surname designation but with different initials, Christian names, partnership and firm identifications thereon, and illustrates the manner in which each card may have a separate numerical identification by means of a sub-number when the main number is the same on several cards. Fig. 4 also illustrates the manner in which surplus digits are crossed out by the chief file clerk in order that the proper number of digits only shall be used by the file clerk.

In my copending application for Letters Patent upon indexing, Serial No. 144,260, from which my present application has been divided, I have described and claimed a novel system of indexing units of subject matter, in which system each unit bears an index number which determines its place in

my novel numerical index, and in accordance with my invention this number alone suffices for all purposes of identification in reference to, filing or finding the unit, and so the clerk, or any person using the index, need have no special skill in such use, but needs only to know the number of the unit in question, as every one of ordinary intelligence is capable of locating any given number in a numerical series indexed as I provide for purposes of removing or back-filing a card or other matter.

The assignment to each unit of its index number, and the physical application of that number to the unit in permanent form, is a single act which may be readily accomplished by a chief filing clerk of moderate attainments, but should be done with care, and must be done in accordance with a pre-determined system by which the numerical indicia are related to, and determined by, selected verbal characteristics or designations of the original subject matter associated with or represented by each index unit, and such preassignment may be according to any system suitable to carry into effect this important feature of my invention, and the physical application of the selected indicia may be accomplished by any suitable means manual or mechanical.

I will now describe the preferred means of effecting the physical application of the indicia to the units, with special reference to Figs. 1 and 2, in which the codifier arrangement appears, and also with reference to Fig. 3 in which the preferred form of codifier apparatus is illustrated, and Fig. 4 in which are shown a few card units upon a sufficiently large scale to exhibit very clearly the numerical indicia associated with the alphabetic designations to which they correspond.

In Fig. 4 the index cards *h* bear respectively the main index number 11127, indicated by the reference character O, and which the codifying or chief file clerk has placed thereon because each of these units is associated with the name "Babcock" as the designatory portion of the matter which these units represent, and in accordance with the selected codifier in Fig. 1, the relation of numeric to alphabetic indicia is

111275
BABCOCK,

and the proper number of these digits—five in the instance illustrated, that being the number of digits used throughout this particular index—have been thus determined by the codifying act of the clerk, once for all, to stand for the designation Babcock, so that the index number 11127 thereafter furnishes a complete and sufficient means of locating all filable matter relating to Babcock entirely independent of whether or

not any person other than the chief file-clerk, referring to the index, finding or back-filing, knows that 11127 means Babcock, or has seen the codifier illustrated in Fig. 1.

In accordance with an important feature of my invention, I have devised a convenient means for enabling the codifying clerk, or any other person using the indexing system, to perform the codifying act mechanically, without a possibility of error in applying the proper index number to the matter, at the time of, and as a part of, the act of applying to said matter the designation selected—in this instance

11127
BABCOCK.

Any suitable means may be adopted for this purpose, and as one convenient form of device I have illustrated in Fig. 2 the characters constituting a font of type in which each letter of the alphabet has arranged above it the number which corresponds thereto according to the selected form of codifier, shown in Fig. 1, the expression "font" not being used in this connection with any limited technical significance, as I prefer to embody the characters, so arranged, in such a convenient imprinting apparatus as a typewriter or addressing machine.

Any suitable typewriter mechanism may be employed, and I have shown in Fig. 3 one convenient form of apparatus which embodies in general a well-known mechanism comprising an oscillating shuttle S provided with a series of type characters arranged according to Fig. 2, in three rows, the middle row containing the alphabetic characters in the order known as that of the "standard" keyboard preferably, to facilitate its operation readily by the typist of usual skill, and the lower row comprising any suitable arrangement of punctuation marks, &c., while the upper row contains exclusively numerical characters corresponding to the codifier order of Fig. 1, and a dash.

In accordance with a valuable feature of my invention, I have thus provided means whereby an operator depressing the several alphabetic keys, (which may be of usual construction, connected with the shuttle S by usual mechanism, and therefore not shown) the respectively corresponding numerical characters will be brought into the position for imprint, so that without the need for any mental selection of the appropriate number, the operator performs the codifying act coincidentally with the ordinary act of depressing the alphabetic key, and the imprint may follow. Any suitable form of platen or impact device may be provided, and as the preferred form of such device I have shown

a well-known form of swinging hammer device T, bearing an adjustable hammer head t secured rotatably in place by a nut t¹ so that it may be turned manually to present 5 for impact any selected hammer face, two such faces being shown in Fig. 3, one bearing the reference character t², and the other t³. Of these faces, the former is constructed, in accordance with a valuable feature of my 10² invention, to provide for imprinting contact with one of the numeric characters of the series s, and at the same time with its relative alphabetic character, these being in vertical alignment on the shuttle S as already 15 described, so that in printing the index number 11127 to codify "Babcock", for example, when the operator depresses the "B" key, the shuttle S will operate to present the combination 20¹ B and the hammer T will swing hammer face t² over for impact simultaneously with the type-faces 1¹ B and these characters will accordingly appear in that relative position upon each article operated upon by the typewriter, whether such article consist of a letter from or to a Babcock, and therefore to be provided by the codifier with the numerical indicia 11127, or if the article 30 be an index card (as h) or a folder, or other unit.

In each case the operation of the typewriter to imprint the name Babcock, will result infallibly in the simultaneous production of the codified superimposed indicia

11127
BABCOCK,

and implicit reliance can be yielded to the accuracy of this relation, owing to the operation by mechanism of imprinting characters acting as a unitary structure, a provision which I claim as broadly novel.

I prefer to provide the hammer head with 45 a face t³ which can be turned into play to effect imprinting impact with the characters of the alphabetic series independently of the numeric series on the shuttle, (or vice versa, by turning the hammer head upside down), 50 and thus the typewriter may be used to produce a typewritten exclusively numerical record when the operator depresses keys bearing exclusively alphabetic designations, a useful arrangement for telegraphic codes, 55 and by transcription of the numeric code upon a decoding typewriter whose keys bear appropriate exclusively numerical designations, cooperating with a hammer head t turned to present its face t³ in position to 60 impact with alphabetic characters only, the decoded verbal message will be reproduced.

If desired, the hammer face t² can be used in the decoding operation, so that the typewritten message will reproduce not only 65 the message in verbal form, but also the

corresponding numerical cipher, associated therewith, and by pasting the original type-written cipher above the re-typewritten cipher an effective means is furnished to check up the accuracy of the decoded verbal 70 message, for if the two numerical records correspond, there can be no discrepancy in the accuracy of the verbal message.

The form of shuttle S illustrated in Fig. 3 can be employed upon the well-known 75 stock and news tickers for transmission electrically of the co-ordinated numerical and alphabetical records, or either of them, and an original record in tape form comprising 80 both numerical and alphabetical equivalents can be cut apart between the two lines of characters, and either may be sent by mail to serve as confirmation of a message transmitted electrically in synchronism with the production of the combined original, thus 85 affording a degree of accuracy heretofore impossible in electrical transmission of secret ciphers.

Another shuttle s¹ may conveniently be 90 provided with an additional series of type-written characters of any well-known character, so that by the usual simple adjustment of the shuttles, s, s¹ on their anvil S and post s³ (the retaining nut s⁴ being raised to effect the adjustment, and replaced thereafter) the series s¹ may be brought into operative position and the series s shifted out of operative position, until required, the typewriter serving thus for ordinary correspondence or other uses without the need for any further mechanical alteration than the adjustment of the proper hammer face t³ for co-operation 95 with the type of series s¹.

The operation of my novel invention is as follows:

When a codifying typewriter is used the chief file clerk first places the card, correspondence or filable matter in the printing position on the typewriter and types the ordinary designation by the usual operation, thus codifying the ordinary designation and placing the numeric filing designation on the matter simultaneously and mechanically accurate, the only remaining operation being to cross out any surplus number digits.

In the accompanying drawings the following rules have been observed, viz: The surname is written first in the case of individual names, the initials or Christian names last; such titles as Dr. Mrs. Mr. Miss, Prof. Hon. etc., being written after the Christian names or initials and being ignored in the composition of the filing number, and likewise the name of a firm or corporation is written as the subject matter gives it, except that conjunctions and prepositions are ignored or placed at the end of the name and not used to form the filing number; abbreviation of any portion of the name is not used if the abbreviation disturbs

the regular sequence of the alphabetic construction of the word in such a manner as to interfere with codifying the necessary number of numeric digits, for example: "Mfg" 5 or "Co." are not "used to abbreviate the words "Manufacturing" and "Company" respectively, but

616
"Manf"

10 and

276
"Com."

can be used as abbreviations since, by codifying, the necessary three number digits are 15 given in proper sequence.

Having illustrated and described my invention thus fully, and suitable means by which the same may be carried into effect, I 20 wish it to be understood that I do not limit myself to the specific materials and constructional forms selected for illustration and description, nor in general do I limit myself otherwise than as set forth in the 25 claims read in connection with this specification.

What I claim as new and desire to secure by Letters Patent is:—

1. The combination with a typewriter, of 30 an imprinting codifier device comprising a series of numeric printing characters and a series of alphabetic printing characters one arranged above the other, and means to effect imprint selectively of characters in 35 either of said series or simultaneously of characters in both of said series.

2. In a codifying typewriter, the combination with an oscillating shuttle having a series of alphabetic printing characters and a superimposed series of numeric printing 40 characters arranged in predetermined relation to said alphabetic characters respectively, of an impressing member having two faces, one long and the other short, movable selectively into imprinting position to cause 45 either the imprint of one or a plurality of characters.

3. In a codifying typewriter, the combination with an oscillating shuttle having a series of alphabetic printing characters and 50 a superimposed series of numeric printing characters, of a hammer having faces arranged one to cause simultaneous imprint of a numeric character and its corresponding alphabetic character, and the other hammer face serving to permit imprint of characters in either of said series selectively. 55

4. A hammer device for typewriters, said device consisting of a rotatable manifold hammer having a codifying face constructed for impact simultaneously with printing characters in two superimposed series, and a face for impact with characters in a selected one of said series. 60

Signed at New York, in the county of 65 New York, and State of New York this 6th day of June, 1917.

CHESTER I. WAGNER.
